PREPARATION OF KETOCHOLANIC ACIDS

Robert H. Sifferd, Clarendon Hills, Ill., assignor
to Armour and Company, Chicago, Ill., a corpora-
tion of Illinois

No Drawing. Continuation of application Serial
No. 548,795, August 9, 1944. This application
March 5, 1948, Serial No. 13,321

7 Claims. (Cl. 260—397.1)

1

This invention relates to the preparation of ketochohanic acids from cholanic acid derivatives, and more particularly to a process for the controlled oxidation of cholanic acid derivatives having a hydroxy group to produce ketochohanic acids therefrom. Such cholanic acid derivatives will be called hydroxychohanic acids in this specification and claims.

This application constitutes a continuation of my copending application Serial No. 548,795 for Preparation of Ketochohanic Acids, filed August 9, 1944, now abandoned.

Dehydrocholesterol acid has heretofore been prepared by the oxidation of cholic acid, but the processes used have not been entirely satisfactory in that the reaction was difficult to handle and control and yields have not been great.

An object of the invention is to provide an efficient economical process for oxidizing hydroxychohanic acids to produce ketochohanic acids. Another object is to provide an oxidation process by which a relatively high yield of a ketochohanic acid may be obtained from a hydroxychohanic acid. Still another object is to provide a process for preparing a ketochohanic acid from a hydroxychohanic acid in which the reaction may be readily handled and controlled. Still a further object is to provide an oxidation process for producing a ketochohanic acid in which a hydroxychohanic acid is slowly and gradually brought into contact with an oxidizing agent to produce a controlled oxidation reaction.

The process contemplates the reaction of a hydroxychohanic acid in an aqueous medium which contains a water-miscible organic solvent in which the hydroxychohanic acid is soluble with a suitable oxidizing agent, such as chromic acid. Preferably, the organic solvent in which the hydroxychohanic acid is soluble is present in a quantity sufficient to dissolve only a portion of the hydroxychohanic acid. Accordingly, as the reaction proceeds and hydroxychohanic acid is converted into the ketochohanic acid, additional hydroxychohanic acid is dissolved and is therefore reacted in solution with the oxidizing agent.

The hydroxychohanic acid may be cholic acid or cholestanic acid, the desoxychohanic acids, lithocholic acids, etc., and may be in any suitable form, such as cholic acid obtained from bile and animal excretions by a process such as that described in my co-pending application Serial No. 517,435, filed January 7, 1944, now Pat. No. 2,438,232, dated March 23, 1948, for Preparation of Cholic Acid.

2

The solution or medium in which the reaction occurs is an aqueous medium containing a water-miscible organic solvent in which the hydroxychohanic acid is soluble. Acetone has been found to be an excellent solvent for this purpose since it is miscible with water, is not readily oxidizable, and is a fairly good solvent for hydroxychohanic acid. Acetone also has the advantage that it is readily available commercially and is relatively inexpensive. Accordingly, it is usually not necessary to recover the acetone used in the process, although this may be done if desired.

Any other water-miscible organic solvent having the desired characteristics and properties may be used. For example, acetic acid or a water-soluble higher aliphatic carboxylic acid may be used. Similarly, higher ketones which are water-miscible, such as methyl ethyl ketone, for example, may be used.

Although any suitable oxidizing agent may be used, chromic acid has been found to be very satisfactory for this purpose. When chromic acid is to be used, the original solution or suspension of the hydroxychohanic acid in the aqueous medium containing the water-miscible inorganic solvent may also contain an acidifying agent so that the reaction may be carried out by mixing the medium containing the hydroxychohanic acid with a chromate salt, such as sodium bichromate. For example, the acidifying agent may consist of sulfuric acid or other suitable acid which does not enter into the reaction.

The hydroxychohanic acid may be suspended with agitation in an aqueous medium containing between 10% and 25% of sulfuric acid and between 15% and 35% of acetone, the proportions being by weight. Preferably, the quantity of sulfuric acid used is in the neighborhood of 20% and the quantity of acetone used is in the neighborhood of 25%. A portion of the hydroxychohanic acid is dissolved in the mixture and the balance of the hydroxychohanic acid is maintained in a dispersion in the medium by means of the agitation.

The oxidation reaction is carried out by adding a suitable oxidizing agent, such as sodium bichromate, to the mixture while violently agitating the entire mixture. During the addition of the oxidizing agent, the mixture will tend to become heated and may be cooled to keep the temperature relatively constant. Preferably, the reaction is carried out at a temperature between 28° C. and 37° C. As the oxidizing agent is added

to the mixture, the hydroxycholanic acid reacts with the oxidizing agent to form the corresponding ketocholanic acid, and additional hydroxycholanic acid becomes dissolved in the mixture and also reacts with the oxidizing agent. In this way, a gradually controlled oxidation of the hydroxycholanic acid is readily carried out.

As the reaction progresses, a ketocholanic acid is formed which separates from the solution, and when the reaction is complete the ketocholanic acid is removed by filtration.

Specific examples of the process are as follows:

Example I

20 lbs. of purified cholic acid is suspended in a mixture of 23 lbs. concentrated sulfuric acid, 50 lbs. of water and 35 lbs. acetone, at a temperature of 30° C. To this mixture is added a water solution of 16 lbs. sodium bichromate, with vigorous agitation and cooling to effect a temperature control in the range of 30°-35° C. After all the bichromate solution has been added, dehydrocholic acid is removed by filtration. It may be purified in any of the usual ways.

Example II

100 lbs. of semi-refined cholic acid is suspended in a mixture of 118 lbs. sulfuric acid, 30 gals. of acetone and 40 gals. of water. To the mixture is added 40 gals. of a water solution containing 85 lbs. technical grade sodium bichromate, keeping the temperature of the mixture between 28° and 37° C. After the bichromate has been added, the dehydrocholic acid formed by the oxidation of the cholic acid is removed by filtration and recrystallized from a suitable solvent.

Although the preferred method of carrying out the reaction is to slowly introduce a water solution of the oxidizing agent, such as sodium bichromate, into the mixture containing the hydroxycholanic acid and vigorously agitating the mixture during the addition, if desired, the hydroxycholanic acid in the medium may be slowly added to the oxidizing agent. In any event, the mixing may be carried out slowly and gradually and a controlled reaction obtained.

As already indicated, the chromic acid or other water-soluble oxidizing agent is added in a quantity greater than that required for reaction with the hydroxy cholanic acid dissolved in the medium. The amount of hydroxy cholanic acid which it is desired to react with the chromic acid is controlled by the quantity of the water-miscible organic solvent introduced. Thus, the amount of hydroxy cholanic acid going into solution, and thereby made available for reaction, is metered by the solvent employed.

The chromic acid or other water-soluble oxidizing agent may be added all at one time or through a period in the process. If the chromic acid is added largely at one time, more cooling coils are required to maintain the desired temperature range. It is more convenient usually to employ less cooling and to feed the oxidizing agent at a slower rate over a period of the operation. For example, the usual operation requires a period of 45 minutes. The chromic acid is preferably introduced slowly into the mixture for from 10 to 30 minutes. After the first 30 minutes of operation, I prefer to agitate the material for another 15 minutes, which completes the operation.

In maintaining the preferred temperatures of 28-37° C., the lower range of temperatures is easily maintained without employing special

cooling means when the chromic acid is introduced at a slow rate. At a selected temperature, the amount of oxidizing agent present in the mixture is greater than that required for reaction with the hydroxy cholanic acid in solution in the medium, and hence the medium effectively serves as a metering for the amount of hydroxy cholanic acid being acted upon by the chromic acid. The operator need observe only the temperature and avoid any excessive feeding of chromic acid which would bring about a temperature rise above the desired reaction temperatures. However, if he desires to add additional chromic acid, this may be done by the addition of increased cooling means.

The process results in a high yield while being accomplished within a very brief interval of time. By the use of the metering step described, in which a selected amount of water-miscible organic solvent is employed, a controlled reaction is effected without carefully observing the amount of oxidizing agent added, thus permitting an extensive reaction between the materials to be carried out in a modicum of time. While the ordinary process requires only 45 minutes, the period may be still further shortened through the use of more extensive cooling means, as above indicated.

If the water-miscible organic solvent were not employed, the addition of the chromic acid would result in rapid oxidation, producing a gummy product and a difficultly-dispersible tar. To avoid this difficulty, it has heretofore been proposed by Eoeedecker (U. S. Patent No. 1,933,003) that xylene be employed as a dispersing agent and that all of the cholic acid be kept out of solution so that oxidation can occur only at the surface interface. The difficulty with this process is the long period of time required for the operation. Since oxidation occurs only at the interface, periods of from 3 to 6 hours are required for the operation, and further it is necessary that the chromic acid be added drop by drop or in small quantities.

In the present process, the oxidation is accomplished in a very short time. Instead of keeping all of the cholic acid out of solution, I put a predetermined amount of cholic acid into solution and oxidize this portion. Further, as the reaction continues, the equilibrium is shifted and more hydroxy cholanic acid goes into solution. If a faster reaction is desired, a greater amount of water-miscible organic solvent is added, or if a slower reaction is desired, a lesser amount of the solvent is added. By metering the amount of hydroxy cholanic acid going into solution through the addition of selected amounts of the organic solvent, the entire reaction can be controlled effectively and completed in a period less than 45 minutes.

Although the invention has been described in connection with certain specific examples, it will be apparent that modifications and changes may be made without departing from the spirit and scope of the invention.

I claim:

1. A process for preparing a ketocholanic acid, comprising dispersing a hydroxycholanic acid in an aqueous medium containing acetone to dissolve only a portion of the hydroxycholanic acid, and mixing the medium having the hydroxycholanic acid dispersed therein with a proportion of a water-soluble oxidizing agent greater than that required for reaction with the hydroxycholanic acid dissolved in said medium.

2. A process for preparing a ketocholanic acid,

comprising dispersing a hydroxycholanic acid in an aqueous medium containing acetone to dissolve only a portion of the hydroxycholanic acid, and slowly mixing a water solution of water-soluble chromate with the medium having the hydroxycholanic acid dispersed therein and in a quantity greater than that required for reaction with said dissolved hydroxycholanic acid.

3. A process for preparing a ketochohanic acid, comprising dispersing a hydroxycholanic acid in an aqueous medium containing a sufficient quantity of acetone to dissolve a portion only of the hydroxycholanic acid, and slowly mixing an aqueous solution of a water-soluble chromate with the medium containing the hydroxycholanic acid dispersed therein while agitating the mixture and maintaining the temperature thereof substantially constant, the chromate solution being added in quantity greater than that required for reaction with the hydroxycholanic acid dissolved in said medium.

4. A process for preparing a ketochohanic acid, comprising dispersing a hydroxycholanic acid in an aqueous medium containing a sufficient quantity of acetone to dissolve a portion only of the hydroxycholanic acid, and slowly mixing an aqueous solution of a water-soluble chromate with the medium containing the dispersed hydroxycholanic acid at a temperature in the neighborhood of 28° C. to 37° C. while agitating the mixture, the mixture containing also an acidifying agent and said oxidizing agent being added in a quantity greater than that required for reaction with the said dissolved hydroxycholanic acid at the time of addition of the hydroxy-

5. A process for preparing a ketochohanic acid, comprising dispersing a hydroxycholanic acid in

an aqueous medium containing an acidifying agent and a sufficient quantity of acetone to dissolve a portion only of the hydroxycholanic acid, and slowly adding to the medium containing the dispersed hydroxycholanic acid an aqueous solution of a water-soluble chromate while maintaining the temperature of the mixture in the neighborhood of 28° C. to 37° C., and agitating the mixture.

10 6. A process for preparing a ketochohanic acid, comprising dispersing a hydroxycholanic acid in an aqueous medium containing in the neighborhood of 15% to 25% sulfuric acid and in the neighborhood of 15% to 35% acetone, the proportions being by weight, and slowly mixing with the medium an aqueous solution of a water-soluble chromate while maintaining the temperature of the mixture in the neighborhood of 28° C. to 37° C., and while agitating the mixture.

15 7. A process for preparing a ketochohanic acid, comprising dispersing a hydroxycholanic acid in an aqueous medium containing a sufficient quantity of acetone to dissolve a portion only of the hydroxycholanic acid, the acetone being in a proportion of about 15% to 35% by weight, and mixing an aqueous solution of a water-soluble oxidizing agent with the medium containing the dispersed hydroxycholanic acid at a temperature of about 28° C. to 37° C.
